RAYMOND R. WALKER, OF FOLLANSBEE, WEST VIRGINIA

COASTER SLED

Application filed November 11, 1930. Serial No. 494,891.

This invention relates broadly to coasters of sled form, and more specifically to steering mechanism for such coasters.

The primary object of the invention is to provide in a coaster, a simple and practical 5 rudder-like device whereby steering of the coaster may readily be effected.

A further object is to provide an improved 10 form of device whereby steering of coaster sleds may be conveniently effected without imposing upon the runners and frame of the sled the bending strains which are inherent to the use of the usual or common forms of 15 steering devices which require that the front ends of the runners be bent or flexed from side to side for directing the course of the sled.

In describing the invention in detail, reference is herein had to the accompanying 20 drawings, in which—

Figure 1 is a top plan view of a coaster sled embodying my invention, the rear end portions of the seating boards being broken away;

Figure 2 is an enlarged top plan view of the 25 rear end portion of the sled;

Figure 3 is a section on line 3—3, Fig. 2;

Figure 4 is a perspective view of the cam 30 face of a disk;

Figure 5 is a rear end elevation of the sled; 35 Figure 6 is a view similar to Fig. 2, illustrating a modification;

Figure 7 is a longitudinal section on line 7—7, Fig. 6; and

Figure 8 is a cross section on line 8—8, 40 Fig. 7.

Referring to said drawings, 1 designates 45 opposite parallel frame members connected by a plurality of cross members 2, and 3 indicates the parallel runners of a sled of an ordinary commercial type, said runners being connected at their front and rear ends to the corresponding ends of the thereto adjacent frame members 1, as by suitably shaped end members 4 and 5. Said runners are also held intermediate their ends in more or less rigid relation to the frame, as by means of 50 angularly disposed rod-like brace members 6 interposed between, and preferably having

their ends welded to, the runners and the cross members 2, as shown.

Rigidly mounted on the under side of the rearmost of the cross members 2 approximately midway between the opposite ends thereof is a horizontally disposed metal disk 7. As herein shown, said rearmost member 2 has formed therein a centrally located ring 8, and the disk 7 is located concentrically with respect to said ring, being permanently and rigidly attached, as by welding, to the latter.

Disposed in parallel underlying relation to said disk 7 is a similar disk 9 which carries in rigid relation thereto, as on the under side thereof, a transversely disposed bar 10 providing opposite laterally extending arms 10'. A pivot-pin or bolt 11 is directed centrally through and connects said disks 7 and 9, the lower end of said bolt carrying an adjusting nut 12 between which and the bar 10 is disposed a spiral spring 14.

The disk 7 has formed on the under face thereof in locations equidistant from its axis a plurality of relatively spaced downwardly extending cam members 13, each of arcuate form in longitudinal section. The disk 9 possesses a form similar to that of the disk 7, but has the cam members 15 thereof formed on its top face. Thus, when the lower disk 9 is rotated either to the right or to the left relative to the fixed upper disk 7, the cam members 15 thereof, normally disposed intermediate the cam members 13 of the upper disk, ride up over the surfaces of said cam members 13 in a manner which will readily be understood, and this action causes said lower disk to be forced downward against the tension of the spring 14, which latter tends normally to maintain said disk in its elevated position and, consequently, to retard rotary movement of said disk in either direction. In the embodiment shown in Figs. 1 to 5, the disks 7 and 9 are formed of heavy sheet metal and have the cam members thereof formed by producing parallel slits in the bodies thereof and by thrusting the metal between said slits outward in the required arcuate form.

Said lower disk 9 has rigidly mounted thereon a rudder 16 which is shown in the present embodiment as formed of a single

length of rod-like material, being shaped to form a runner-like member 16' adapted to engage the ground or roadway between the sled runners 3, upwardly and forwardly inclined front and rear end members 17 and 18, and relatively alined and approaching terminal members 19 and 20 which are rigidly attached, as by welding, to the under face of said disk 9.

10 In the normal elevated position of said disk 9, the rudder is supported with the runner member 16' thereof in, or slightly elevated with respect to, the plane occupied by the sled runners 3. However, when rotary 15 movement in either direction is imparted to said disk 9, the latter is resultantly depressed to the extent that the runner member 16' of the thereby carried rudder is thrust into close bearing engagement with the surface of the 20 ground or pathway upon which the sled travels and said member is at the same time shifted out of parallel alinement with the sled runners, thereby, through engagement with the ground, to effect a corresponding 25 shifting of the course of travel of the sled.

Suitable additional means is preferably provided for supporting and steadyng the rudder in its normal inoperative position, the means herein shown including a seat formed 30 by the provision of a recess, as 21, in the under side of a cross member 2 located forward of that which carries the disk 7, said seat being adapted for the reception of a portion of the foremost member 20 of the terminals 35 of the rudder, as shown in Figs. 7 and 8.

The means by which the operator controls the direction of travel of the sled comprises a transverse steering bar 22 pivoted intermediate its ends, as at 23, upon a stationary 40 part, as a seating board 24, at the front end of the sled. Crossed cables or rods 25 connect the opposite end portions of said steering bar 22 to the opposite ends or arms 10' of the transverse bar 10.

45 Manifestly, forwardly directed force applied by the operator to an end of said steering bar 22 is transmitted through the intermediate cable 25 to the opposite end of the bar 10 for producing rotary movement of the disk 9 in the direction which effects shifting of the rudder to incline the latter toward, or more nearly toward, the point of the force application. Immediately following the release of the applied steering force, 55 the tension spring 14 actuates return rotary movement of said disk 9 and, consequently, elevating movement of said rudder to a non-steering position.

In the modified form shown in Figs. 6 and 60 7, upper and lower disks 7^a and 9^a are substituted for the disks 7 and 9 hereinbefore described, the former having a substantially flat face and being rigidly carried by the ring or loop 8 of the cross member 2 and the 65 disk 9^a being pivotally attached on the un-

der side of the disk 7^a, as by means of a bolt 11^a, and having the rudder suitably fixed thereto. The bar 10 is in turn rigidly carried on the under side of said disk 9^a. Retractile coil springs 26 have their inner ends 70 attached to opposite sides of the rudder 16 and their opposite ends to adjacent stationary parts or members, as to the rear end portions of the adjacent frame members 1, as shown. Said springs function to return the rudder to its normal position following use of the latter in changing the course of the sled.

What is claimed is—

1. In a coaster sled having a manually 80 shiftable steering member, a pair of pivotally related elements, one of said elements being rigidly mounted on the rear end of the top frame of the sled, the other of said elements being carried by and rotatable relative to said fixed element, said elements having relatively interengageable cam surfaces formed on confronting faces thereof, a roadway-contacting rudder carried by said rotary element, resilient means normally tending to maintain said rotary element in an elevated position wherein said rudder is rendered inoperative, and means intermediate said steering member and said rotary element whereby shifting movements imparted to the former actuates rotary movements of the latter for causing said cam surfaces to cooperate for effecting depression of said rudder to operative position for predeterminedly changing the course of travel of the sled. 90

2. In a coaster sled, a pair of pivotally related disks having relatively spaced cam members on their confronting faces, one of said disks being rigidly mounted on the rear end of the top frame of the sled, the other of said disks being carried by and rotatable relative to said fixed disk, a roadway-contacting rudder carried in fixed relation to said rotary disk, said rotary disk having its cam members movable into and out of riding relation to the cam members of said fixed disk in rotary movements thereof whereby said rudder is lowered into and elevated from operative relation to the roadway, resilient means tending normally to maintain said rotary disk in the position wherein said rudder occupies its elevated inoperative position, a manually shiftable member on the front portion of the sled, and means intermediate said shiftable member and said rotary disk whereby movements imparted to the former actuate rotary movements of the latter for effecting simultaneous lowering and angular shifting of said rudder. 115

3. In a coaster sled, a pair of pivotally related disks having relatively spaced cam members on their confronting faces, one of said disks being rigidly mounted on the rear end of the top frame of the sled, the other 130

- of said disks being rotatable relative to said fixed disk, a rudder having a road-contacting portion normally occupying parallel relation to the runners of the sled, said rudder being carried in fixed relation to said rotary disk, said rotary disk having the cam members thereof movable into and out of riding relation to the cam members of the fixed disk in rotary movements thereof whereby said rudder is lowered into and elevated out of engagement with the roadway, resilient means tending normally to maintain said rotary disk in the position wherein said rudder is elevated, a manually shiftable member on the front end of the sled, and means interposed between the last mentioned member and said rotary disk whereby movements of the former actuate predetermined rotary movements of the latter for effecting simultaneous lowering and angular shifting movements of said rudder. 5
4. In a coaster sled, a frame, parallel runners, a member mounted for rotary movements on said frame, a rudder supported by said rotary member and adapted to engage the roadway for directing the course of the sled, resilient means normally holding said member elevated to a position wherein said rudder clears the roadway, manually shiftable means having connection with said member for imparting rotary movement to the latter whereby said rudder is shifted out of parallel relation to said runners, and means operative to depress said rotary member for lowering said rudder into road engaging position when said rudder is shifted out of parallel relation to said runners, the last mentioned means including interengageable cam elements carried by the frame and the rotary member. 10
5. In a coaster sled, a frame, parallel runners, a member mounted for rotary movements on said frame, a rudder supported by and depending from said rotary member, said rudder being vertically shiftable into and out of engagement with the roadway for directing the course of the sled, a spring normally holding said rotary member in an elevated position wherein said rudder is elevated from the roadway, manually shiftable means carried by the frame, means connecting said shiftable means to said rotary member whereby movements of the former are communicated to the latter for effecting corresponding lateral shifting movements of said rudder, and interengageable cam elements borne, respectively, by said frame and said rotary member and operative against the holding force of said spring to lower said rotary member when the latter is rotated to dispose said rudder in non-parallel relation to said runners. 15
6. In a coaster sled, a frame, parallel runners, a fixed member carried by said frame, a member mounted for rotary movements on
- the under side of said fixed member, resilient means normally tending to maintain said rotary member in an elevated position, said members having cam surfaces on their confronting faces adapted to cooperate in movements of said rotary member for lowering the latter against the force exerted by said resilient means, a rudder supported by said rotary member and having a part adapted in the lowered position of said member to engage the roadway for directing the course of the sled, a manually shiftable transverse steering bar pivoted on the frame, and means connecting the opposite ends of said bar to said rotary member whereby shifting movements of the former actuate rotary movements of the latter for shifting said rudder to dispose its said roadway engaging part in angular relation to said runners. 20
7. In a coaster sled having a manually shiftable steering member, a pair of pivotally related elements having cam surfaces formed on their confronting faces, one of said elements being rigidly mounted on the frame of the sled, the other of said elements being supported by and rotatable relative to said fixed elements for disposing said cam surfaces of the elements in and out of riding relation, a spring normally holding said rotary element elevated relative to said fixed element, a roadway contacting rudder carried by said rotary element, a pivotally mounted steering member, and means intermediate said steering member and said rotary element whereby shifting movements of the former actuate rotary movements of the latter for changing the angular relation of said rudder to the sled runners. 25
8. In a coaster vehicle including a frame and a manually shiftable steering member, a pair of pivotally related elements embodying interengageable cam surfaces, one of said elements being fixed to said frame and the other being adapted for simultaneous rotary and vertical shifting movements relative to said fixed element, resilient means normally tending to maintain said rotary element in elevated position, a rudder device movable into and out of vehicle-guiding contact with the roadway with lowering and elevating movements of said rotary element, and means intermediate said steering member and said rotary element whereby manual shifting of the former actuates rudder-lowering rotary movement of the latter. 30
- In testimony whereof, I affix my signature.
